UNITED STATES PATENT OFFICE.

HOMER W. RIGHTMYER, OF ROWLESBURG, WEST VIRGINIA.

TOY PISTOL.

SPECIFICATION forming part of Letters Patent No. 653,697, dated July 17, 1900.

Application filed March 30, 1900. Serial No. 10,781. (No model.)

To all whom it may concern:

Be it known that I, HOMER W. RIGHTMYER, a citizen of the United States, residing at Rowlesburg, in the county of Preston and State of West Virginia, have invented certain new and useful Improvements in Toy Pistols; and I do hereby declare the following to be a full, clear, and exact description of the invention, such as will enable others skilled in the art to which it appertains to make and use the same.

The purpose of the present invention is to improve, simplify, and cheapen the construction of the toy pistol covered by Letters Patent No. 624,543, granted to me May 9, 1899. In this patented pistol the hammer was provided above its pivot and outside the frame with a hook which pulled the fulminate-strip backward over a bridge-piece forming a permanent part of the frame, and a strip-holder which had no connection with the trigger was arranged to be struck by the trigger and operated to hold the strip against retrograde movement when the hammer was falling.

5 The means for cocking the hammer consisted of a link which was separate from the trigger-spring, but was arranged to be pressed upwardly into operative relation with the hammer-notch by an extension of the spring.

o In the present improvements the fulminate-strip is fed in the opposite direction, and the strip-feeder is connected to the hammer below its pivot and is inclosed within the frame. There is also provided a slide or cut-off to prevent the explosion of the fulminate from igniting those on the strip which have not arrived at the firing-point and to protect the works from the refuse of the exploded fulminates, and this slide is operated by the hammer. The separate cocking-link of the patented construction is entirely dispensed with and the trigger-spring is provided with a return bend or loop extending backwardly from its connection with the trigger, and this loop performs the function of the separate link in the former construction. The trigger-spring also has an extension projecting forwardly beyond the notch of the hammer into such position as to be pressed against the fulminate-strip when the trigger is pulled, so as to act as a strip-holder and prevent retrograde movement when the hammer falls. The parts

are thus greatly simplified, and the trigger-spring is made to perform the three functions of, first, holding the trigger; second, 55 cocking the hammer, and, third, acting as a strip-holder.

The improved construction is shown in the accompanying drawings, wherein—

Figures 1 and 2 are similar sectional views 60 with the parts in different positions, and Fig. 3 is a plan view.

The frame of the pistol, including the barrel and the hammer, is made in halves 3 4, as indicated in Fig. 3, and these halves are 65 permanently secured together by rivets 5 6 after the working parts have been secured in place within the frame.

The trigger *t* and the hammer *7* are substantially the same in construction as in my 70 former patent, except that the hammer is provided with an extension *p* in front and beneath its pivot for the purpose of operating a strip-feeder *f'*, which consists of a light spring *f*, having its forward end connected to 75 the extension and its rear end extending backwardly within the handle and bearing on the front wall of the same, so as to hold the forward end of the feeder with a light spring-pressure against the fulminate-strip. The 80 mainspring for the hammer is denoted by *S*. It is in all respects the same as in the patented construction. The trigger-spring *s* is connected in any suitable manner at its rear end with in the hollow handle, and its forward end is 85 connected to the trigger at a point above its pivot in the manner indicated in the drawings. From its connection with the trigger this spring has a return bend or loop *s²*, which extends backwardly and is then bent laterally, 90 so as to engage the notch *n* in the heel of the hammer. It is then bent forwardly again on the opposite side of the hammer and forms the strip-holder *e*. The separate cocking-loop of my former patent is dispensed with and the 95 loop is made integral with the trigger-spring and is given the proper bend, so as to spring automatically into the notch of the hammer when the trigger is released.

The roll of fulminate is inclosed in the 100 frame in the usual manner; but I provide a cover-plate *8*, which is arched, as shown in the drawings, and pivoted on the rivet *6*, which holds the two parts of the frame to-

gether. This cover-plate is recessed on its under side to form a magazine for the fulminate-strip, and the rear edge forms a bridge or anvil over which the strip is fed and against which the fulminates are exploded by the hammer when the cover is closed.

In order to prevent the explosion of one fulminate from accidentally igniting those on the strip which have not yet reached the firing-point and protect the works from the refuse of the exploded fulminates, I provide a slide *a* and connect it with the hammer by passing the latter through a slot in the rear end of the slide. As the hammer rises the slide is withdrawn, as indicated in Fig. 2; but when the hammer falls to explode the fulminates the slide is carried forward, so as to act as a cut-off and close the interior of the frame against the entrance of the flame.

20. In order to load the pistol, the cap-plate *8* is lifted into the position shown in dotted lines in Fig. 2, and the end of the fulminate-strip is brought around on the under side of the bridge, so as to be fed forward by the feeder *f* each time that the hammer is cocked.

The operation of the parts will be readily understood on examination of the drawings. Normally the strip-feeder *f* and the strip-holder *e* stand as shown in Fig. 1; but when the trigger is pulled the feeder *f* rises with the extension *p* of the hammer, and the strip-holder is also advanced by the same movement. When the hammer has been entirely cocked and the cocking-loop *s* slips out of the notch *n*, the strip-feeder returns to its original position and the strip-holder *e* is by the backward pull on the trigger pressed against the strip, so as to hold it momentarily against retrograde movement.

25. Having thus described my invention, what I claim, and desire to secure by Letters Patent, is—

30. 1. In a toy pistol, the combination of the bridge over which the fulminate-strip is advanced, the hammer, the strip-feeder con-

nected to the hammer, the trigger, and the spring *s*, the latter being secured at one end in the handle and connected with the trigger, said spring having also a return-bend forming a hook to engage the cocking-notch of the 50 hammer.

2. In a toy pistol, the combination of the bridge over which the fulminate-strip is advanced, the hammer, the strip-feeder connected to the hammer, the trigger, and the 55 spring *s*, the latter being at one end in the handle and connected with the trigger, said spring having also a return-bend forming a hook to engage the cocking-notch of the hammer, and a forward extension *e*, to hold the 60 strip and prevent retrograde movement when the hammer falls.

3. In a toy pistol, the combination of the bridge over which the fulminate-strip is advanced, the hammer having the projection *p*, 65 and the spring *f* attached to the projection *p*, and having its rear end bearing in the handle-case, and its front end extended to form a strip-feeder *f*.

4. In a toy pistol, the combination of the bridge over which the fulminate-strip is advanced, a strip-feeder *f* connected to the hammer below and forward of its pivot, and a slide *a* connected to the hammer above its pivot to form a cut-off and prevent the refuse 75 from entering the case.

5. In a toy pistol, the combination of the frame, the hammer, the trigger, the strip-feeder, and the cover-plate *8*, pivoted to the frame at *b*, and having the bridge *b* over 80 which the fulminate-strip is fed, said plate being recessed on its under side to form a magazine to hold the roll of fulminate.

In testimony whereof I affix my signature in presence of two witnesses.

HOMER W. RIGHTMYER.
